United States Patent Office

Des. 183,505
Patented Sept. 9, 1958

183,505

AUTOMOBILE GRILLE UNIT OR THE LIKE

Peter W. Wozena, Detroit, Mich., assignor to General
Motors Corporation, Detroit, Mich., a corporation of Delaware

Application February 13, 1958, Serial No. 49,630

Term of patent 7 years

(Cl. D54—2)

Figure 1 is a perspective view of an automobile grille unit or the like showing my new design;

I claim:

The ornamental design for an automobile grille unit or the like, substantially as shown.
